United States Patent Office

Des. 198,372
Patented June 9, 1964

198,372

CHAIR

Herbert Ritts, 2221 S. Sepulveda Blvd., Los Angeles, Calif.

Filed Dec. 16, 1963, Ser. No. 77,813

Term of patent 7 years

(Cl. D15—1)

I claim:

The ornamental design for a chair, substantially as shown.
